UNITED STATES PATENT OFFICE.

HARRY A. HOUSEMAN, OF PHILADELPHIA, PENNSYLVANIA, ASSIGNOR TO
STANDARD MACHINE COMPANY, OF PHILADELPHIA, PENNSYLVANIA,
A CORPORATION OF PENNSYLVANIA.

CIRCULAR-KNITTING MACHINE.

SPECIFICATION forming part of Letters Patent No. 779,423, dated January 10, 1905.

Application filed October 31, 1902. Serial No. 129,521.

To all whom it may concern:

Be it known that I, HARRY A. HOUSEMAN, a citizen of the United States, residing at Philadelphia, county of Philadelphia, and State of Pennsylvania, have invented a new and useful Improvement in Circular-Knitting Machines, of which the following is a full, clear, and exact description, reference being had to the accompanying drawings, which form a part of this specification.

The object of my invention is an improved circular-knitting machine which will automatically and without stoppage of the machine produce a seamless stocking having a lace or tuck stitch upon the front of the leg, the instep, and upper portion of the stocking, tuck stitch work upon the rear of the leg, and plain stitches upon the heel, toe, and sole of the foot.

20 In a previous patent issued to me, No. 654,347, dated July 24, 1900, I have shown, described, and claimed devices so combined in a circular-knitting machine that tuckwork is formed in a seamless stocking upon certain 25 of the needles used to form the front of the leg, the instep, and the top of the foot.

In my present invention I provide, in addition to the above, separate mechanism that will form tuck-stitches upon certain needles 30 used to form the back of the leg of the stocking. The last-mentioned mechanism is automatically and in the operation of the machine thrown out of action during the formation of the heel, toe, and sole, while during the formation of the leg the two tuck-stitch mechanisms operate in unison and uniformly. A circular-knitting machine embodying my improvements will knit a stocking such, for instance, as is shown and described in Letters 35 Patent of the United States No. 702,843 in the continuous operation of the machine.

40 For the general construction of the circular-knitting machine to which my improvements have been added reference may be had to Letters Patent No. 538,518, issued to me April 30, 1895.

In the drawings, Figure 1 is a side elevation of a part of my improved knitting-machine. Fig. 2 is a side elevation of the oper-

ating-cam and its driving mechanism. Fig. 3 is a plan view of the same. Fig. 4 is a plan view of pattern-plates. Fig. 5 is a side elevation of the machine. Fig. 6 is a section through a portion of the cylinder, showing the operating-levers and their connections. Fig. 7 is an enlarged side elevation of portion of machine. Fig. 8 is a top plan view of machine with thread-guide omitted, showing the action of lever 16, dotted lines showing position of parts before action and full lines while in action. Fig. 9 is a view similar to Fig. 8, with lever 13 in action. Fig. 10 is a detail sectional view of switch-cam and its support. Fig. 11 is a detail elevation, partially in section, showing levers 13 and 16 and block 3 and appurtenant mechanism. Fig. 12 is a detail perspective view of block 3. Fig. 13 is an elevation of the interior of the cam-cylinder. Fig. 14 is an elevation showing the levers 13 and 16. Fig. 13^a is an enlarged view showing a portion of the wall of the cam-cylinder with its cut-away portion and tongue and the block 3 resting therein. Fig. 15 is a diagrammatic view showing the action of the switch or needle cam when in its high position upon the long and short latched needles. Fig. 16 is a similar view with the needle or switch cam in its low position.

The machine of Patent No. 538,518, as is well known, consists of an operating-cam cylinder A, which is driven by the gear B upon the shaft b, which shaft b is rotated by means of the bevel-gear c on the driving-shaft D, meshing with the gear c' loose upon the shaft b and reciprocated by means of the gear D', also loose upon the shaft b, operated by the rack D². By means of the clutch D², feathered upon the shaft b, the shaft b is connected with either the rotary gear c' or reciprocating gear D', and thus the cam-cylinder rotated or reciprocated. The needles are held in levers E' and F². The levers E' control those needles which in the manufacture of circular goods, such as stockings, are during the formation of the heel and toe thrown out of action. In the operation of this machine, as is fully set out in the Patent No. 538,518, last mentioned, before the levers E' are at the desired point

in the knitting they are automatically operated upon to throw them out of action by a plate F, in which the tails of the levers E' rest, the plate having depending rods f, which 5 are operated upon by mechanism described in said patent to move the rods and plate. In order to operate upon the desired number of levers E' and their corresponding needles to throw certain of the needles in and out of action for predetermined rotation of the cam-cylinder, and thus form the tuck-stitch, I add the following mechanism to this part of the machine:

I make my levers E' with bifurcated ends 15 e e'. The plate F is formed with a cut-away portion f', beveled at its lower surface f'', in which the end e' rests. Upon the top of this plate F is a pattern-plate f''' removably secured thereto and which projects into the space 20 between the ends e e' of levers E'. In this plate f''' corresponding to the levers desired to be acted upon in the formation of the open or lace work of the fabric, are orifices f'''' of a size sufficient to allow the tail e' of 25 lever E' to pass up through them. For the rods f, connected to the plate F, I use tubes. Superimposed upon the pattern-plate f''' is a second pattern-plate f'''', removably secured to the plate F'. The plate F' has a cut-away 30 portion in which the end e of lever E' rests. The pattern-plate f'''' has a portion which projects into the space between the ends e e' of the levers E', and the thickness of the plates f''' f'''' is equal to the space between said ends. 35 The upper surface of this plate f'''' is beveled. In this pattern-plate f'''' corresponding to the levers which are not desired to be acted upon in the formation of the open or lace work of the fabric, are cut-away portions f'''' 40 of a size sufficient to allow the tails e' of the levers E' to pass through. Secured to the plate F' by nuts f'''' are the rods f'''' and f''''', which pass through orifices in the pattern-plates f''' and f''''' and plate F and through the 45 tubes f. The lower end of rod f'''' passes into an orifice g in the lever G, and by means of a nut g' the vertical height of the rod f'''' may be adjusted. This lever G is secured to the rock-shaft G'. The lower end of rod f''''' is correspondingly secured to a lever G'', which is 50 also secured to the rock-shaft G'. The end of lever G opposite the shaft G' has upon it the cam-plate g''. Upon the rods f'''' and f''''' are the springs f'''''. 55 H is a lever pivoted to the frame of the machine at h and having at one end the cam-plate h', adapted to operate the cam-plate g''. When the lever G is in the position shown in Fig. 1, the rods f'''' f''''' are lowered and the 60 needles acted on by the plate F' are in action. When the plate F' is moved to the position shown in Fig. 6, the cam-plate h' operates on the cam-plate g'' and through it upon the lever G, lifting the rods f'''' f''''' and elevating plate F' and certain of the needle-levers E', throw-

ing those needle-levers and their needles out of action. I operate this lever H as follows: j j' are pins upon the lever H below the pivot-point h. J is a superposed plate having a roller J' at its lower end and slots j'' j''' through 70 which the pins j j' project. K' K'' are two cams secured upon the face of the gear-wheel K. The cam K' projects from the face of the gear-wheel a greater distance than does cam K''. The roller J' is normally in such position 75 that it rests against the cam K' at a point above the cam K''. The cam K' is so formed that in the revolution of the wheel it maintains the lever H in the position shown in Fig. 1 or returns it to that position. In order to 80 bring the roller J' under the influence of both cams K' and K'' and remove it from such influence, I provide the following mechanism: l is a projection from plate J, which by means of link l' is connected to bell-crank lever 85 L, one arm of which has at its end the toe-piece l'' and below the end the pin l''', to which is connected a spring l''', which normally holds the bell-crank L and the plate J in the position shown in Fig. 1 in contact only with the 90 cam K'. In this position the toe-piece l'' is in line with a pattern-chain M upon the shaft m. Upon this chain is the lug M'. This lug in its movement strikes the toe-piece l'', moving the bell-crank L against the action of the spring 95 l''', depressing the plate J, and bringing the roller J' into operative relation with both cams K' and K'' at different portions of the gear-wheel K. In the specific illustration shown in the 100 drawings the gear-wheel K is intended to make one revolution for three revolutions of the cam-cylinder, and, as shown, the cam K' controls during one-third of the revolution and the cam K'' during two-thirds of the revolution 105 when both are acting. Thus when the bell-crank has been acted on by the lug on the pattern-chain, as just described, the lever H will be acted on to throw the predetermined needles out of action for two revolutions of the cam-cylinder and in action for one revolution. The lever L is locked in its position after action upon it by the lug M' on the pattern-chain by reason of the pivoted latch N, which by gravity 110 engages the pin l'''. The latch N is released 115 and the bell-crank L returned to its initial position by the projection N' on the pattern-chain M, which strikes the latch N, lifting it, and the spring l''''' draws the bell-crank L to its initial position, lifting the plate J, bringing the 120 roller J' into action only with the cam K', and the cam K' will operate the lever H and the plate F' to bring the levers E' into action. The position of the cam K' with reference to the gear K is such as to make it operative, so 125 that the needles will be thrown into action at the proper time. With my mechanism in order to arrange which of the needles are to be thrown in and out of action during the formation of the lace or open work it is only nec- 130

essary to arrange the pattern-plates f^3 and f^5 —that is, provide orifices in the plate f^3 corresponding to the tails of the levers E' desired to be thus operated and orifices in the plate f^5 corresponding to the tails of the levers E' not desired to be then operated. By having a series of these plates with orifices at different points change of pattern may be obtained by merely changing the pattern-plates. While I have described the cams K' and K^2 as being such that in one revolution thereof the cam K^2 acts through two-thirds of the revolution and the cam K' one-third and that they are designed to run as one revolution for three revolutions of the cam-cylinder, this may be varied, as it may be desirable to have the needle stitch every second course or only every fourth course, and this would only require a change of extent of rotation and relative revolution of the cams.

The preceding description relates to that part of the machine which is used to form the lace-work upon the front of the stocking and with the needles which are thrown out of action during the formation of the heel and toe and which is disclosed in Patent No. 654,347. I will now describe the additional features over those of the last-mentioned patent and which form the subject-matter of the present invention. The particular object of these additional features or devices is to provide tuck-stitching upon certain fashioning-needles $Z' Z'$ during the formation of leg of the stocking, and thus form a tuck-stitch all around the leg of the stocking and yet have no tuck-stitching upon these needles during the formation of the heel, toe, and sole. Further, I so connect the tuck-stitching mechanism of these fashioning-needles with the tuck-stitching mechanism of the non-fashioning needles, before described, that when the tuck-stitching mechanism of the fashioning-needles is in operation the tuck-stitching will be uniform throughout. The fashioning-needles, as is well known, in circular-knitting machines are those needles which are used to form the back of the stocking, the heel, toe, and sole. They are termed "fashioning-needles" because in the formation of the heel and toe their number is gradually reduced course by course until the fabric is narrowed down and then gradually increased course by course until the full number are again in use. This is called "fashioning," and the needles used in this operation are termed "fashioning-needles." They comprise one-half of the needles and are in practice placed in the front half of the machine. Speaking generally, the tuck-stitching upon the fashioning-needles is accomplished in the following manner: Such of the fashioning-needles which I intend to use to form tuck-strokes I form with latches of extra length, so that in the normal position of such needles the regular throw-off cam of the machine will not in its ordinary

position lift the needles high enough to throw off the stitch. These needles are lettered Z' . I also arrange this throw-off cam so that it can be elevated to such a level that these tuck-stitch fashioning-needles, as well as the remaining fashioning-needles, will be elevated high enough to throw off the stitch. Thus it may be seen that with the throw-off cam in its normal position the fashioning tuck-stitch needles will receive but not cast off a stitch. I also provide mechanism or devices for lifting the regular throw-off cam to a level or height that will throw off the stitches upon the fashioning tuck-stitch needles. I also connect the mechanism for lifting this throw-off cam so that it is lifted during rotary work of the machine during the same course that the mechanism to operate the non-fashioning tuck-stitch needles to throw off their stitches acts. I also provide mechanism which will operate the cam-lifting mechanism so that the cam is elevated and maintained elevated during reciprocating work of the machine (forming the heel and toe) and during the formation of the sole.

I will now describe the specific mechanism illustrated in the drawings for accomplishing the above purposes. The wall of the cam-cylinder A is cut away, forming the slot having the projecting tongues 2 . In this slot rests the block 3 , having the vertical slots 4 , in which rest the tongues 2 . Between the top of the block 3 and the under surface of the top of the cam-cylinder is the spring 5 , tending to hold the block at its lower point. The block has the projecting cam-face 6 , which projects outwardly beyond the cam-cylinder.

The stitch-cams of my machine, speaking generally, are shown in Letters Patent No. 521,860, dated June 26, 1894, granted to me. As shown in that patent and in the drawings illustrating my present invention, I use as a part of the stitch-cams the switch-cams 7 , each of which normally rests against a corresponding stitch-cam 12 . As in my previous patent mentioned, each of these switch-cams 7 has a pin 8 secured to it, which pin rests in an orifice 8^a in the cam-cylinder, and a spring-actuated pin 8^b bears against said pin 8 . The function of these switch-cams 7 of the stitch-cams is in ordinary knitting both reciprocation and rotation to determine the direction of the travel of the needle, whether above or below the stitch-cam 12 . Its operation is clearly described in my previous patent spoken of and may be stated here as follows: The movement of the cam-cylinder causes a switch-cam 7 to strike a needle. If it is the upper surface of this switch-cam which strikes the needle, the needle follows that surface toward the top of the stitch-cam 12 . If it is the under surface of the switch-cam 7 which strikes, the needle lifts the switch-cam at that point, allowing the needle to pass. In the present machine the function of these switch-cams, so

far as the purpose heretofore described is concerned, is the same as in the previous patent mentioned.

In my improved construction in addition to the above one of the switch-cams—as shown, the left-hand switch-cam—is provided at or near one end with a pin 10, which rests in a horizontal slot 11 in the block 3, so that while still connected as in my Patent No. 521,860 its upper surface will by the vertical movement of the block be elevated or depressed—*i. e.*, is vertically movable. When at its lower position, its height is such that in the passage of the needles over it before reaching the stitch-cams 12 the long-latched needles are not elevated sufficiently to throw off the stitch, while the short-latched needles are elevated sufficiently to throw off their stitches. (See Fig. 16.) When the block is elevated, the upper surface of the cam 7 is elevated sufficiently to lift both the long and short latched needles, so as to release the stitch. (See Fig. 15.)

13 is a lever or plate pivoted at 14 upon a plate 17, secured to the cam-cylinder, and having the projection 15, adapted when the lever 13 is swung to move under and operate upon the cam-face 6 of the block 3 and lift the block. This lever or plate 13 has also the projecting portion 15'. The plate or lever 13 is also pivoted at 13' to a second plate or lever 16, which latter lever is also pivoted at 16' to the plate 17; but the plate or lever 13 is at a higher level than the plate or lever 16. The plate or lever 16 has also a projecting portion 18. Secured loosely upon, so as to be movable around the upright 19, is the arm 20, held in frictional contact therewith by the pin 20'. The outer end of this arm is provided with the cam-face or operating-cam 21.

22 is a frame secured to the upright 23 and loosely surrounding the upright 19. In a projection 24 from frame 22 is the set-screw 25, and a spring 26 connects the arm 20 and frame 22. By lifting either upright 19 or 23 the arm 20 is lifted. When it is lifted, the cam-face 21 is in line with the projecting portion 15' of the lever 13 and in the rotation of the cam-cylinder is acted on to lift the block 3 and the cam 7 to a position to throw off the stitch on both the long and short latched fashioning-needles. When the uprights 19 and 23 are down, the cam-face 21 is in line with the projection 18 of lever 16, which by the previous action has been moved into such alinement, and in the rotation of the cam-cylinder moves said lever and through it the lever 13, releasing the block 3, which by the action of its spring returns to its low position, bringing the switch-cam 7 to the low position, where only the short-latched needles of the fashioning-needles cast their stitch. (See Figs. 8 and 9.) The upright 19 is supported and guided so as to be movable and is provided with the spring 27, tending to hold

it in its lower position. The end of this upright 19 rests upon one end of the pivoted frame 28, the other end of the frame 28 being connected to a connecting-rod 29, which in turn is connected to the crank 29' upon the shaft G'. The upright 23 is also guided so as to have a vertical movement. The lower end of this upright has the collar 30, which is provided with the projection 31, under which one end 32 of the pivoted gravity dog or catch 33 is adapted to rest. This dog or catch 33 has the cut-away portion 34.

36 is the frame to which the shifting-rods 37 for the clutch D' are connected. This frame 36 is connected to the upright 38, operated by the clutch-shifting cam 39 and frame 46, all as in Patent No. 538,518, heretofore referred to, and for shifting the clutch to change the connection of the cam-cylinder from rotation to reciprocation. Projecting from and connected to the frame 36 is arm 41, having at its upper end the lateral projection 42 and the vertical projection 43. Upon the lower end of the upright 23 is the projection 44, having the tailpiece 45. The cut-away portion 34 of the catch 33 is in line of movement of projection 43 and the projection 44 in line of movement of lateral projection 42. The pattern-chain M has also upon it the lug 50. The revolution of pattern-chain is so timed and the lug 50 so arranged upon it that the lug strikes the tailpiece 45 at the time the body of the foot is being formed.

From the foregoing the operation of the machine may be readily understood. When the leg of the stocking is started to be formed, the uprights 19 and 23 are both down (see Fig. 7) and the lever 13 free from the block 3 and the switch-cam down, so that the long-latched fashioning-needles will not lose their stitch. During the rotation of the cylinder forming the leg at each time the rock-shaft G' is operated to throw off the stitch upon the tuck-stitch needles of the non-fashioning needles, as before described, the upright 19 is lifted by means of the frame 28 and connecting-rod 29. The elevation of the upright 19 has no effect upon upright 23, but lifts the arm 20, so that the cam-face 21 is in line with the projection 15' of lever 13, and when in the rotation of the machine it is struck by said lever the lever turns, lifting the block 3 and bringing the switch-cam 7 to the high level, so as to throw off the stitches upon both the short and the long latch fashioning-needles. (See Fig. 15.) When the upright 19 descends, due to the downward movement of the frame 28 imparted by the connecting-rod 29 and the rock-shaft G', the cam-face 21 is brought in line with the projection 18 of lever 16, and when struck by said projection the lever 13 is moved to bring the end free from the block 3 and the block by the action of its spring descends and the cam 7 is brought to the low point, so that the long-latch fashioning-needles

dles take the thread but do not cast the stitch, while the short - latched fashioning - needles both take and cast the stitch. (See Fig. 16.) When the clutch-shifting cam 39 is operated to 5 shift the connection of the cam-cylinder from the rotary mechanism to the reciprocating mechanism, (forming the heel or toe,) the arm 41 is lifted, bringing the projection 42 against the projection 44, lifting the upright 10 23 and through it the upright 19, bringing the cam 21 in alinement with the projection 15' of lever 15, thus forcing the cam 7 to its high point, where all the fashioning-needles will 15 cast the stitches. The movement of the arm 15 41 also moves the vertical projection 43 against the cut-away portion 34 of catch 33, holding the catch out. This position is maintained during the entire reciprocation, and thus during this period none of the fashioning-needles form tuck - stitches. When the 20 shift of the cam 39 is made to change the cam-cylinder-operating mechanism from reciprocation to rotation, the arm 41 descends, releasing the upright 23, which will then descend 25 and bring the cam 21 in alinement with the projection 18 of lever 16, releasing the block and bringing the cam 7 to its low point. If, however, this last-mentioned shift from reciprocation of the cam-cylinder to rotation be 30 for the formation of the foot, the lug 50 on the pattern-chain strikes the tailpiece 45, the upright 23 is lifted or held lifted, and the catch 33 holds it there until the shift is made again to and from reciprocation. Thus by this construction the tuck-stitching upon the fashioning-needles during the formation of the leg of 35 the stocking is formed corresponding to that formed upon the non - fashioning needles. Again, where the fashioning-needles are used 40 in the formation of the heel or toe or sole of the foot tuck-stitches are formed upon none of them. The reason for pivoting the arm carrying the cam 21 and making it freely yielding in one direction is that it will yield 45 if for any reason during the reciprocation of the machine it should be struck.

Having now fully described my invention, what I claim, and desire to protect by Letters Patent, is—

50 1. In a circular - knitting machine of the character described, in combination, a needle-cylinder, fashioning-needles in said cylinder, mechanism to throw the fashioning-needles out of and into action for the purpose of narrowing and widening the fabric, non-fashioning needles in said cylinder, a cam-cylinder and means to rotate and reciprocate said cam-cylinder, mechanism for actuating certain of the fashioning-needles to form tuck-stitches, 55 mechanism for actuating certain of the non-fashioning needles to form tuck-stitches, and means for operating said mechanisms uniformly and simultaneously during the rotation of the cam-cylinder.

60 2. In a circular - knitting machine of the

character described, in combination, a needle-cylinder, fashioning-needles in said cylinder, mechanism to throw the fashioning-needles out of and into action for the purpose of narrowing and widening the fabric, non-fashioning needles in said cylinder, a cam-cylinder, and means to rotate and reciprocate said cam-cylinder, mechanism for actuating certain of the fashioning-needles to form tuck-stitches, mechanism for actuating certain of the non-fashioning needles to form tuck-stitches, and means to operate said mechanisms uniformly and simultaneously during the rotation of the cam-cylinder, and means for throwing the fashioning-needle tuck-stitch actuating mechanism out of operation during the reciprocation of said cam-cylinder. 70

3. In a circular - knitting machine, of the character described, in combination, a needle-cylinder, fashioning-needles in said cylinder, mechanism to throw the fashioning-needles out of and into action for the purpose of narrowing and widening the fabric, non-fashioning needles in said cylinder, a cam-cylinder, means to rotate and reciprocate said cam-cylinder, mechanism for actuating certain of the fashioning - needles to form tuck - stitches, mechanism for actuating certain of the non-fashioning needles to form tuck-stitches, and means for operating said mechanism uniformly and simultaneously during the rotation of the cam-cylinder and means in the operation of the machine to throw the fashioning-needle tuck-stitch mechanism out of operation during the reciprocation of said cam-cylinder. 80

4. In a circular - knitting machine of the character described, in combination, a needle-cylinder, fashioning-needles in said cylinder, mechanism to throw the fashioning-needles out of and into action for the purpose of narrowing and widening the fabric, non-fashioning needles in said cylinder, a cam-cylinder, means to rotate and reciprocate said cam-cylinder, mechanism for actuating certain of the fashioning-needles to form tuck-stitches thereon, mechanism for actuating certain of the non-fashioning needles to form tuck-stitches thereon, and means for operating said mechanisms uniformly and simultaneously during the rotation of the cylinder, forming the leg of a stocking, and means to throw the fashioning-needle tuck-stitch mechanism out of operation during the operation of said machine to form the heel, toe and foot of said stocking. 90

5. In a circular - knitting machine of the character described, in combination, a needle-cylinder, fashioning-needles in said cylinder, mechanism to throw said fashioning-needles out of and into action for the purpose of narrowing and widening the fabric, non-fashioning needles in said cylinder, a cam-cylinder, means to rotate and reciprocate said cam-cylinder, mechanism for operating certain of the fashioning-needles to form tuck-stitches. 100

105

110

115

120

125

- thereon, mechanism for operating certain of the non - fashioning needles to form tuck-stitches thereon, and means for operating said mechanism uniformly and simultaneously during the rotation of the cylinder forming the leg of a stocking, and means to throw the fashioning tuck-stitch mechanism out of operation during the shift of said machine to form the toe, heel and foot of said stocking.
6. In a circular-knitting machine of the character described, in combination, a needle-cylinder, fashioning-needles in said cylinder, mechanism to throw said needles out of and into action for the purpose of narrowing and widening the fabric and non-fashioning needles in said cylinder, a cam-cylinder, mechanism adapted to operate certain of the non-fashioning needles to form tuck-stitches therewith, a needle-lifting cam secured to said cylinder so as to be vertically movable to form tuck-stitches upon certain of the fashioning-needles and connection between the non-fashioning tuck-stitch-operating mechanism and said cam to operate said cam and the non-fashioning tuck-stitch-needle mechanism simultaneously and uniformly.
7. In a circular-knitting machine of the character described, in combination, a needle-cylinder, fashioning-needles in said cylinder, mechanism to throw said fashioning-needles out of and into action for the purpose of narrowing and widening the fabric, non-fashioning needles in said cylinder, a cam-cylinder, mechanism adapted to operate certain of the non-fashioning needles to form tuck-stitches therewith, a needle-lifting cam secured to said cylinder so as to be vertically movable to form tuck-stitches upon certain of the fashioning-needles and connection between the non-fashioning tuck-stitch-needle mechanism simultaneously and uniformly, and means to hold and maintain said cam in its elevated position independent of said fashioning tuck-stitch-needle-operating mechanism.
8. In a circular-knitting machine of the character described, in combination, a needle-cylinder, fashioning-needles in said cylinder, mechanism to throw said needles out of and into action for the purpose of narrowing and widening the fabric, non-fashioning needles in said cylinder, tucking mechanism for certain of the non-fashioning needles, a cam-cylinder, a rock-shaft for operating the non-fashioning-needles tucking mechanism, tucking mechanism for certain of the fashioning-needles, and connection between said fashioning-needle tucking mechanism and said rock-shaft whereby said fashioning-needle tucking mechanism is operated by said rock-shaft.
9. In a circular-knitting machine of the character described, in combination, a needle-cylinder, fashioning-needles in said cylinder, mechanism to throw said needles out of and into action for the purpose of narrowing and widening the fabric, non-fashioning needles in said cylinder, a cam-cylinder, a rock-shaft for operating the non-fashioning-needles tucking mechanism, tucking mechanism for certain of the fashioning-needles, and connection between said fashioning-needle tucking mechanism and said rock-shaft whereby said fashioning-needle tucking mechanism is operated by said rock-shaft.
10. In a circular-knitting machine of the character described, in combination, a needle-cylinder, fashioning-needles in said cylinder, mechanism to throw said needles out of and into action for the purpose of narrowing and widening the fabric, non-fashioning needles in said cylinder, tucking mechanism for certain of the non-fashioning needles, a cam-cylinder, a rock-shaft for operating the non-fashioning-needles tucking mechanism, a needle-lifting cam secured to said cylinder so as to be vertically movable, connection between said cam and said rock-shaft, whereby in the operation of said shaft the needle-lifting cam is lifted, and means to lift and hold said needle-lifting cam in its elevated position independent of the rock-shaft.
11. In a circular-knitting machine of the character described, in combination, a needle-cylinder, fashioning-needles in said cylinder, mechanism to throw said needles out of and into action for the purpose of narrowing and widening the fabric, non-fashioning needles in said cylinder, tucking mechanism for certain of the non-fashioning needles, a cam-cylinder, a rock-shaft for controlling the tuck-stitch-needles mechanism, a needle-lifting cam secured to said cylinder so as to be vertically movable, connection between said cam and said rock-shaft, whereby in the operation of said shaft the needle-lifting cam is lifted, and means to lift and hold said needle-lifting cam in its elevated position independent of the rock-shaft at predetermined times during the operation of the machine.
12. In a circular-knitting machine of the character described, in combination with the cam-cylinder, a rock-shaft and mechanism to rock said shaft in a predetermined manner, a needle-lifting cam secured to said cam-cylinder so as to be vertically movable and connection between said cam and said rock-shaft whereby, in the operation of said shaft, said needle-lifting cam is elevated and depressed, and means to lift and hold said needle-lifting cam in its elevated position independent of the rock-shaft.
13. In a circular-knitting machine of the character described, in combination with the cam-cylinder, a rock-shaft and mechanism to

rock said shaft in a predetermined manner, a needle-lifting cam secured to said cam-cylinder so as to be vertically movable and connection between said cam and said rock-shaft whereby, in the operation of said shaft, said needle-lifting cam is elevated and depressed, and means to lift and hold said needle-lifting cam in its elevated position independent of the rock-shaft at predetermined times during the operation of the machine.

14. In a circular-knitting machine of the character described, in combination with the cam-cylinder, of a needle-lifting cam secured thereto so as to be vertically movable, a vertically-movable operating-cam independent of the cam-cylinder, intermediate mechanism carried by the cam-cylinder adapted when struck by said operating-cam in its elevated position to raise said needle-lifting cam and when struck by said operating-cam in its depressed position to release said needle-lifting cam and means to elevate and depress said lifting-cam.

15. In a circular-knitting machine, of the character described, in combination with the cam-cylinder, of a needle-lifting cam secured thereto so as to be vertically movable, a vertically-movable operating-cam independent of the cam-cylinder, intermediate mechanism carried by the cam-cylinder adapted when struck by said operating-cam in its elevated position to raise said needle-operating cam and when struck by said operating-cam in its depressed position to release said needle-lifting cam, a rock-shaft and connection between said operating-cam and said rock-shaft whereby said lifting-cam is elevated and depressed in the operation of said rock-shaft.

16. In a circular-knitting machine of the character described, in combination with the cam-cylinder, of a needle-lifting cam secured thereto so as to be vertically movable, a vertically-movable operating-cam independent of the cam-cylinder, intermediate mechanism carried by the cam-cylinder adapted when struck by said operating-cam in its elevated position to raise said needle-operating cam and when struck by said operating-cam in its depressed position to release said needle-lifting cam, a rock-shaft and connections between said lifting-cam and said rock-shaft whereby said operating-cam is elevated and depressed in the operation of said rock-shaft, and means to elevate and maintain said operating-cam elevated independent of said rock-shaft.

17. In a circular - knitting machine of the character described, in combination, a needle-cylinder, fashioning-needles in said cylinder, mechanism to throw said fashioning-needles out of and into action for the purpose of narrowing and widening the fabric, non-fashioning needles in said needle-cylinder, a cam-cylinder mechanism for operating certain of the non - fashioning needles to produce tuck-

stitches, a rock-shaft for operating the non-fashioning-needles tuck-stitch mechanism, of a needle-lifting cam secured to said cam-cylinder so as to be vertically movable, a vertically-movable operating-cam independent of the cam - cylinder, intermediate mechanism carried by the cam - cylinder adapted when struck by said operating-cam in its elevated position to raise said needle-lifting cam and when struck by said needle-operating cam in its depressed position to release said needle-lifting cam, and connection between said operating-cam and said rock-shaft whereby said operating-cam is elevated and depressed in the operation of said rock-shaft.

18. In a circular - knitting machine of the character described, in combination, a needle-cylinder, fashioning-needles in said cylinder, mechanism to throw said fashioning-needles out of and into action for the purpose of narrowing and widening the fabric, non-fashioning needles in said needle-cylinder, the cam-cylinder mechanism for operating certain of the non-fashioning needles to produce tuck-stitches, a rock-shaft for operating the non-fashioning-needles tuck-stitch mechanism, of a needle-lifting cam secured to the cam-cylinder so as to be vertically movable, a vertically-movable operating-cam independent of the cam - cylinder, intermediate mechanism carried by the cam - cylinder adapted when struck by said operating-cam in its elevated position to raise said needle-lifting cam and when struck by said operating-cam in its depressed position to release said needle-lifting cam, and connection between said operating-cam and said rock-shaft whereby said operating-cam is elevated and depressed in the operation of said rock-shaft, and means to elevate and maintain said operating-cam elevated independent of said rock-shaft.

19. In a circular - knitting machine of the character described, in combination with the cam - cylinder, a needle - lifting cam secured thereto so as to be vertically movable, a vertically-movable operating-cam independent of the cam - cylinder, intermediate mechanism carried by the cam - cylinder adapted when struck by said operating-cam in its elevated position to raise said needle-lifting cam and when struck by said operating-cam in its depressed position to release said needle-lifting cam, a pattern-chain having a lug and a device connected to said operating-cam adapted when struck by said lug to lift said operating-cam, and a locking-pawl adapted to hold said operating-cam in its elevated position.

20. In a circular-knitting machine of the character described, in combination with the cam-cylinder, of a needle-lifting cam secured thereto so as to be vertically movable, a vertically-movable operating-cam independent of the cam-cylinder, intermediate mechanism carried by the cam-cylinder adapted when struck by said operating-cam in its elevated

position to raise said needle-lifting cam and when struck by said operating-cam in its depressed position to release said needle-lifting cam and a locking-pawl adapted to hold said 5 operating-cam in its elevated position, clutch-shifting mechanism for changing the connection of the cam-cylinder from rotation to reciprocation, and vice versa and connection between said operating-cam and said clutch-shifting mechanism adapted in the movement of the clutch-shifting mechanism in one direction to lift said cam and release said clutch.

21. In a circular-knitting machine of the character described, in combination with the 15 cam-cylinder, and stitch-cams, one of which is secured so as to be vertically movable, and mechanism adapted, when operated, to elevate and depress said vertically-movable stitch-cam, a cam for operating said vertically-movable stitch-cam mechanism, said cam in one position operating said mechanism to elevate said vertically-movable cam, and in the other direction to release said cam, a movable upright to which said operating-cam is 20 operatively connected, a needle-cylinder, fashioning-needles in said cylinder, mechanism to throw said needles out of and into action for the purpose of narrowing and widening the fabric, non-fashioning needles in said cylinder, 25 a rock-shaft for controlling the non-fashioning tuck-stitch needles, and connection between said rock-shaft and said operating-cam.

22. In a circular-knitting machine of the character described, in combination with the 30 cam-cylinder, a needle-lifting cam secured thereto so as to be vertically movable and mechanism adapted when operated to elevate and depress said needle-lifting cam, of a cam for operating said needle-lifting-cam mechanism, said cam in one position operating said mechanism to elevate said needle-lifting cam and in the other direction to release said cam, a movable upright to which said operating-cam is operatively connected, clutch-shifting 35 mechanism for changing the connection of the cam-cylinder from rotation to reciprocation and vice versa, having a projection carried thereby, a projection upon said upright in line of movement of said clutch-shifting-mechanism projection.

23. In a circular-knitting machine of the character described, in combination with the cam-cylinder, a needle-lifting cam secured thereto so as to be vertically movable and 40 mechanism adapted when operated to elevate and depress said needle-lifting cam, of a cam for operating said needle-lifting-cam mechanism, said cam in one position operating said mechanism to elevate said needle-lifting cam and in the other direction to release said cam, a movable upright to which said operating-cam is operatively connected, a pattern-chain having a lug, a projection from said upright adapted to be struck by said lug and move 45 said upright.

24. In a circular-knitting machine of the character described, in combination with the cam-cylinder, a needle-lifting cam secured thereto so as to be vertically movable and mechanism adapted when operated to elevate and depress said needle-lifting cam, of a cam for operating said needle-lifting-cam mechanism, said cam in one position operating said mechanism to elevate said needle-lifting cam and in the other direction to release said cam, a movable upright to which said operating-cam is operatively connected, a pattern-chain having a lug, a projection from said upright adapted to be struck by said lug and move 50 said upright, and a locking-pawl adapted to hold said upright in its moved position.

25. In a circular-knitting machine of the character described, in combination with the cam-cylinder, a needle-lifting cam secured thereto so as to be vertically movable and mechanism adapted when operated to elevate and depress said needle-lifting cam, of a cam operating said needle-lifting-cam mechanism, said cam in one position operating said mechanism to elevate said needle-lifting cam and 55 in the other direction to release said cam, a movable upright to which said operating-cam is operatively connected, a pattern-chain having a lug, a projection from said upright adapted to be struck by said lug, and move 60 said upright, and a locking-pawl adapted to hold said upright in its moved position, clutch-shifting mechanism for changing the connection of the cam-cylinder from rotation to reciprocation and vice versa, a projection upon said upright in line of movement of said clutch-shifting-mechanism projection, said locking-pawl being also in line of movement of said clutch-shifting-mechanism projection.

26. In a circular-knitting machine of the character described, in combination with the cam-cylinder, a needle-lifting cam secured thereto so as to be vertically movable and mechanism adapted when operated to elevate and depress said needle-lifting cam, an operating-cam for operating said needle-lifting-cam mechanism, said cam in one position operating said mechanism to elevate said needle-lifting cam and in the other position to release said cam, vertically-movable uprights as 19 and 23, said 65 operating-cam being fixedly connected to one upright 19 and severally connected with the other upright 23, whereby said operating-cam is moved in the movement of either upright, but has a movement with upright 19 independent of the movement of upright 23, a needle-cylinder, fashioning-needles in said cylinder, mechanism to throw said fashioning-needles out of and into action for the purpose of narrowing and widening the fabric, non-fashioning needles in said needle-cylinder, tucking mechanism for certain of the non-fashioning needles, a rock-shaft for controlling the non-fashioning needles, tucking mechanism and connection between said rock-shaft 70 and

and the upright 19, a projection from said upright 23, clutch-shifting mechanism for changing the connection of the cam-cylinder from rotation to reciprocation and vice versa, having a projection carried thereby, said projection from upright 23, being in line of movement of said clutch-shifting-mechanism projection.

27. In a circular-knitting machine of the character described, in combination with the cam-cylinder, a needle-lifting cam secured thereto so as to be vertically movable and mechanism adapted when operated to elevate and depress said needle-lifting cam, of a cam for operating said needle-lifting-cam mechanism, said cam in one position operating said mechanism to elevate said needle-lifting cam and in the other position to release said cam, vertically-movable uprights as 19 and 23, said operating-cam being fixedly connected to one upright 19 and severably connected to the other upright 23, whereby said operating-cam is moved in the movement of either upright, but has a movement with upright 19 independent of the movement of upright 23, a needle-cylinder, fashioning-needles in said cylinder, mechanism to throw said fashioning-needles out of and into action for the purpose of narrowing and widening the fabric, non-fashioning needles in said needle-cylinder, tucking mechanism for certain of the non-fashioning needles, a rock-shaft for controlling the non-fashioning needles, tucking mechanism and connection between said rock-shaft and the upright 19, a projection from said upright 23, a pattern-chain, a lug upon said pattern-chain, the projection from said upright 23 being in line of movement of said lug.

28. In a circular-knitting machine of the character described, in combination with the cam-cylinder, a needle-lifting cam secured thereto so as to be vertically movable and mechanism adapted when operated to elevate and depress said needle-lifting cam, of a cam for operating said needle-lifting-cam mechanism, said cam in one position operating said mechanism to elevate said needle-lifting cam and in the other position to release said cam, vertically-movable uprights as 19 and 23, said operating-cam being fixedly connected to one upright 19, and severably connected to the other upright 23, the connection being such that said operating-cam is moved in the movement of either upright, but has a movement with upright 19 independent of the movement of upright 23, a needle-cylinder, fashioning-needles in said cylinder, mechanism to throw said fashioning-needles out of and into action for the purpose of narrowing and widening the fabric, non-fashioning needles in said needle-cylinder, tucking mechanism for certain of the non-fashioning needles, a rock-shaft for controlling the non-fashioning needles, tucking mechanism and connection between said rock-shaft and the upright 19, a projection from said upright 23, a pattern-chain, a lug upon said pattern-chain, the projection from said upright 23 being in line of movement of said lug.

projection from said upright 23, a pattern-chain, a lug upon said pattern-chain, the projection from said upright 23 being in line of movement of said lug and a locking-pawl adapted to hold said upright when moved by 70 said lug.

29. In a circular-knitting machine of the character described, in combination with the cam-cylinder, a needle-lifting cam secured thereto so as to be vertically movable and mechanism adapted when operated to elevate and depress said needle-lifting cam, of a cam for operating said needle-lifting-cam mechanism, said cam in one position operating said mechanism to elevate said needle-lifting cam 80 and in the other position to release said cam, vertically-movable uprights as 19 and 23, said operating-cam being fixedly connected to one upright 19 and severably connected to the other upright 23, the connection being such 85 that said operating-cam is moved in the movement of either upright, but has a movement with upright 19 independent of the movement of upright 23, a needle-cylinder, fashioning-needles in said cylinder, mechanism to throw said fashioning-needles out of and into action for the purpose of narrowing and widening the fabric, non-fashioning needles in said needle-cylinder, tucking mechanism for certain 90 of the non-fashioning needles, a rock-shaft for controlling the non-fashioning needles, tucking mechanism and connection between said rock-shaft, and the upright 19, a projection from said upright 23, a pattern-chain, a lug upon said pattern-chain, the projection from 95 said upright 23 being in line of movement of said lug and a locking-pawl adapted to hold said upright when moved by said lug, clutch-shifting mechanism for changing the connections of the cam-cylinder from rotation to reciprocation and vice versa, a projection from 100 said clutch-shifting mechanism, said pawl being in line of movement of said clutch-shifting-mechanism projection and released when struck thereby.

30. In a machine of the character described, in combination with the cam-cylinder and stitch-cams, one of which is movably attached to said cam-cylinder, of a block secured to the cam-cylinder so as to be vertically movable, said block having a horizontal slot, said last-mentioned cam having a pin resting in said slot, said block having a cam-face projecting beyond said cam-cylinder, a lever adapted when brought against said cam-face 115 120 to elevate said block, and means to move said lever against and away from said block projection.

31. In a machine of the character described, in combination with the cam-cylinder and 125 stitch-cams, one of which is movably attached to said cam-cylinder, of a block secured to the cam-cylinder so as to be vertically movable, said block having a horizontal slot, said last-mentioned cam having a pin resting in said slot, 130

said block having a cam-face projecting beyond said cam-cylinder, a lever adapted when brought against said cam-face, to elevate said block, and means to move said lever against 5 and away from said block projection at pre-arranged times.

32. In a machine of the character described, in combination with the cam-cylinder and stitch-cams, one of which is movably attached 10 to said cylinder, of a block secured to the cam-cylinder so as to be vertically movable, said block having a horizontal slot, said last-mentioned cam having a pin resting in said slot, said block having a cam-face projecting beyond said cam-cylinder, a lever adapted when brought against said cam-face to elevate said block, and means to move said lever against and away from said block projection, and a 15 spring against the action of which said block 20 is elevated.

33. In a machine of the character described, in combination with the cam-cylinder and stitch-cams, one of which is movably attached to said cylinder, of a block secured to the cam-cylinder so as to be vertically movable, said block having a horizontal slot, said last-mentioned cam having a pin resting in said slot, said block having a cam-face projecting beyond said cam-cylinder, a lever adapted when 25 brought against said cam-face to elevate said block, and means to move said lever against and away from said block projection at pre-arranged times, and a spring against the action of which said block is elevated.

34. In a machine of the character described, in combination with the cam-cylinder and stitch-cams, one of which is movably attached to said cylinder, of a block secured to the cam-cylinder so as to be vertically movable, said 30 block having a horizontal slot, said last-mentioned cam having a pin resting in said slot, said block having a cam-face projecting beyond said cam-cylinder, a lever adapted when brought against said cam-face to elevate said block, a second lever to which the first-mentioned lever is attached, the first-mentioned lever when struck by the cam being moved against the block projection, and the second-mentioned lever when struck causing the 35 first-mentioned lever to be withdrawn from said block projection, a cam adapted to be brought in line with either lever, and means to operate said last-mentioned cam in a pre-arranged manner.

35. In a machine of the character described, in combination with the cam-cylinder and stitch-cams, one of which is movably attached to said cam-cylinder, of a block secured to the cam-cylinder so as to be vertically movable, 40 said block having a horizontal slot, said last-mentioned cam having a pin resting in said slot, said block having a cam-face projecting beyond said cam-cylinder, a lever adapted when brought against said cam-face to elevate said block, a second lever to which the first-

mentioned lever is attached, the first-mentioned lever when struck by the cam being moved against the block projection, and the second-mentioned lever when struck by the cam causing the first-mentioned lever to be withdrawn from said block projection, a cam 70 adapted to be brought in line with either lever, and means to operate said last-mentioned cam in a prearranged manner, and a spring against the action of which said block is ele- 75 vated.

36. In a machine of the character described, in combination with the cam-cylinder and stitch-cams, one of which is movably attached to said cam-cylinder, of a block secured to the 80 cam-cylinder so as to be vertically movable, said block having a horizontal slot, said last-mentioned cam having a pin resting in said slot, said block having a cam-face projecting beyond said cam-cylinder, a lever adapted when 85 brought against said cam-face to elevate said block, a second lever to which the first-mentioned lever is attached, the first-mentioned lever when struck by the cam being moved against the block projection and the second-mentioned lever when struck by the cam moving the first-mentioned lever away from said 90 block projection, said levers being at different levels, a cam adapted to operate said levers, a vertically-movable upright to which 95 said cam is connected so as to move with said uprights, a rock-shaft and connection between said rock-shaft and said upright, and means to operate said rock-shaft in a predetermined manner.

37. In a machine of the character described, in combination with the cam-cylinder and stitch-cams, one of which is movably attached to said cam-cylinder, of a block secured to the cam-cylinder so as to be vertically movable, 100 said block having a horizontal slot, said last-mentioned cam having a pin resting in said slot, said block having a cam-face projecting beyond said cam-cylinder, a lever adapted when brought against said cam-face to elevate 105 said block, a second lever to which the first-mentioned lever is attached, the first-mentioned lever when struck by the cam being moved against the block projection, and the second-mentioned lever when struck causing the 110 first-mentioned lever to be withdrawn from said block projection, a cam adapted to be brought in line with either lever, and means to operate said last-mentioned cam in a pre-arranged manner.

38. In a machine of the character described, 115 in combination with the cam-cylinder and a needle-lifting cam pivotally attached thereto, of a block secured to the cam-cylinder so as to be vertically movable, said block having a horizontal slot, said needle-lifting cam having 120

100

105

110

120

125

130

a pin resting in said slot, said block having a cam-face projecting beyond said cam-cylinder, a lever adapted when brought against said cam-face to elevate said block, a second lever to which the first-mentioned lever is attached, the first-mentioned lever when struck being brought against the block projection and the second-mentioned lever when struck causing the first-mentioned lever to be withdrawn from said block projection, said levers being at different levels, a cam adapted to operate said levers, a vertically-movable upright to which said cam is connected so as to move with said upright, a projection from said upright, clutch-shifting mechanism for changing the cam-cylinder mechanism from rotation to reciprocation and vice versa, a projection from said clutch-shifting mechanism, the upright projection being in line of movement of said clutch-shifting-mechanism projection.

39. In a machine of the character described, in combination with the cam-cylinder and a needle-lifting cam pivotally attached thereto, of a block secured to the cam-cylinder so as to be vertically movable, said block having a horizontal slot, said needle-lifting cam having a pin resting in said slot, said block having a cam-face projecting beyond said cam-cylinder, a lever adapted when brought against said cam-face to elevate said block, a second lever to which the first-mentioned lever is attached, the first-mentioned lever when struck being brought against the block projection and the second-mentioned lever when struck causing the first-mentioned lever to be withdrawn from said block projection, said levers being at different levels, a cam adapted to operate said levers, a vertically-movable upright to which said cam is connected so as to move with said upright, a pattern-chain, a lug thereon, a projection from said upright in line of movement of said lug, and a locking-pawl adapted to hold said upright when moved by said lug, clutch-shifting mechanism for changing the connection of the cam-cylinder from rotation to reciprocation and vice versa, a projection from said clutch-shifting mechanism, said locking-pawl being in line of movement of said clutch-shifting-mechanism projection.

40. In a machine of the character described, in combination with the cam-cylinder and a needle-lifting cam pivotally attached thereto, of a block secured to the cam-cylinder so as to be vertically movable, said block having a horizontal slot, said needle-lifting cam having a pin resting in said slot, said block having a cam-face projecting beyond said cam-cylinder, a lever adapted when brought against said cam-face to elevate said block, a second lever to which the first-mentioned lever is attached, the first-mentioned lever when struck being brought against the block projection and the second-mentioned lever when struck causing the first-mentioned lever to be withdrawn from said block projection, said levers being at different levels, a cam adapted to operate said levers, a vertically-movable upright to which said cam is connected so as to move with said upright, a pattern-chain, a lug thereon, a projection from said upright in line of movement of said lug, and a locking-pawl

adapted to hold said upright when moved by said lug.

41. In a machine of the character described, in combination with the cam-cylinder and a needle-lifting cam pivotally attached thereto, of a block secured to the cam-cylinder so as to be vertically movable, said block having a horizontal slot, said needle-lifting cam having a pin resting in said slot, said block having a cam-face projecting beyond said cam-cylinder, a lever adapted when brought against said cam-face to elevate said block, a second lever to which the first-mentioned lever is attached, the first-mentioned lever when struck being brought against the block projection and the second-mentioned lever when struck causing the first-mentioned lever to be withdrawn from said block projection, said levers being at different levels, a cam adapted to operate said levers, a vertically-movable upright to which said cam is connected so as to move with said upright, a pattern-chain, a lug thereon, a projection from said upright in line of movement of said lug, and a locking-pawl adapted to hold said upright when moved by said lug, clutch-shifting mechanism for changing the connection of the cam-cylinder from rotation to reciprocation and vice versa, a projection from said clutch-shifting mechanism, said locking-pawl being in line of movement of said clutch-shifting-mechanism projection.

42. In a machine of the character described, in combination, with the cam-cylinder and a needle-lifting cam pivotally attached thereto, of a block secured to the cam-cylinder so as to be vertically movable, said block having a horizontal slot, said needle-lifting cam having a pin resting in said slot, said block having a cam-face projecting beyond said cam-cylinder, a lever adapted when brought against said cam-face to elevate said block, a second lever to which the first-mentioned lever is attached, the first-mentioned lever when struck being brought against the block projection and the second-mentioned lever when struck causing the first-mentioned lever to be withdrawn from said block projection, said levers being at different levels, a cam adapted to operate said levers, vertically-movable uprights as 19 and 23, said lever-operating cam being connected to both uprights so as to move when either upright moves but having a movement with upright 19 independent of upright 23, a needle-cylinder, fashioning-needles in said cylinder, mechanism to throw said fashioning-needles out of and into action for the purpose of narrowing and widening the fabric, non-fashioning needles in said needle-cylinder, tucking mechanism for certain of the non-fashioning needles, a rock-shaft for controlling the non-fashioning-needles tucking mechanism and connection between said rock-shaft and the upright 19, a projection from said upright 23, clutch-shifting mechanism for chang-

ing the connection of the cam-cylinder from rotation to reciprocation and vice versa, having a projection carried thereby, said projection from upright 23 being in line of movement of said clutch-shifting-mechanism projection.

43. In a machine of the character described, in combination with the cam-cylinder and a needle-lifting cam pivotally attached thereto, 10 of a block secured to the cam-cylinder so as to be vertically movable, said block having a horizontal slot, said needle-lifting cam having a pin resting in said slot, said block having a cam-face projecting beyond said cam-cylinder, 15 a lever adapted when brought against said cam-face to elevate said block, a second lever to which the first-mentioned lever is attached, the first-mentioned lever when struck being brought against the block projection and the 20 second-mentioned lever when struck causing the first-mentioned lever to be withdrawn from said block projection, said levers being at different levels, a cam adapted to operate said levers, vertically-movable uprights as 19 25 and 23, said lever-operating cam being connected to both uprights so as to move when either upright moves but having a movement with upright 19 independent of upright 23, a needle-cylinder, fashioning-needles in said cylinder, mechanism to throw said fashioning-needles out of and into action for the purpose of narrowing and widening the fabric, non-fashioning needles in said needle-cylinder, tucking mechanism for certain of the non-fashioning needles, a rock-shaft for controlling 30 the non-fashioning-needles tucking mechanism and connection between said rock-shaft and the upright 19, a projection from said upright 23, a pattern-chain, a lug upon said pattern-chain, the projection from said upright 23 being in line of movement of said lug, and a locking-pawl adapted to hold said upright when moved by said lug.

44. In a machine of the character described, in combination with the cam-cylinder and a needle-lifting cam pivotally attached thereto, 45 of a block secured to the cam-cylinder so as to be vertically movable, said block having a horizontal slot said needle-lifting cam having a pin resting in said slot, said block having a cam-face projecting beyond said cam-cylinder, 50 a lever adapted when brought against said cam-face to elevate said block, a second lever to which the first-mentioned lever is attached, the first-mentioned lever when struck being brought against the block projection and the 55 second-mentioned lever when struck causing the first-mentioned lever to be withdrawn from said block projection, said levers being at different levels, a cam adapted to operate said levers, vertically-movable uprights as 19 and 23, said lever-operating cam being connected to both uprights so as to move when either upright moves but having a movement with upright 19 independent of upright 23, a needle-cylinder, fashioning-needles in said cylinder, mechanism to throw said fashioning-needles out of and into action for the purpose of narrowing and widening the fabric, non-fashioning needles in said needle-cylinder, tucking 60 mechanism for certain of the non-fashioning needles, a rock-shaft for controlling the non-fashioning-needles tucking mechanism and connection between said rock-shaft and the upright 19, a projection from said upright 23, a pattern-chain, a lug upon said pattern-chain, the projection from said upright 23 being in line of movement of said lug, a locking-pawl adapted to hold said upright when moved by said lug, and clutch-shifting mechanism for 65 changing the connections of the cam-cylinder from rotation to reciprocation and vice versa, a projection from said clutch-shifting mechanism, said pawl being in line of movement of said clutch-shifting-mechanism projection and released when struck thereby.

46. In a circular-knitting machine of the character described, in combination, a needle-cylinder, fashioning-needles in said cylinder, mechanism to throw said fashioning-needles out of and into action for the purpose of narrowing and widening the fabric, non-fashioning needles in said cylinder, a cam-cylinder and means to rotate and reciprocate said cam-cylinder, of mechanism for actuating certain of 70 75 80 85 90 95 100 105 110 115 120 125 130

needles out of and into action for the purpose of narrowing and widening the fabric, non-fashioning needles in said needle-cylinder, tucking mechanism for certain of the non-fashioning needles, a rock-shaft for controlling the non-fashioning-needles tucking mechanism and connection between said rock-shaft and the upright 19, a projection from said upright 23, a pattern-chain, a lug upon said pattern-chain, the projection from said upright 23 being in line of movement of said lug, and a locking-pawl adapted to hold said upright when moved by said lug.

45. In a machine of the character described, in combination with the cam-cylinder and a needle-lifting cam pivotally attached thereto, of a block secured to the cam-cylinder so as to be vertically movable, said block having a horizontal slot, said needle-lifting cam having a pin resting in said slot, said block having a cam-face projecting beyond said cam-cylinder, a lever adapted when brought against said cam-face to elevate said block, a second lever to which the first-mentioned lever is attached, the first-mentioned lever when struck being brought against the block projection and the second-mentioned lever when struck causing the first-mentioned lever to be withdrawn from said block projection, said levers being at different levels, a cam adapted to operate said levers, vertically-movable uprights as 19 and 23, said lever-operating cam being connected to both uprights so as to move when either upright moves but having a movement with upright 19 independent of upright 23, a needle-cylinder, fashioning-needles in said cylinder, mechanism to throw said fashioning-needles out of and into action for the purpose of narrowing and widening the fabric, non-fashioning needles in said needle-cylinder, tucking mechanism for certain of the non-fashioning needles, a rock-shaft for controlling the non-fashioning-needles tucking mechanism and connection between said rock-shaft and the upright 19, a projection from said upright 23, a pattern-chain, a lug upon said pattern-chain, the projection from said upright 23 being in line of movement of said lug, a locking-pawl adapted to hold said upright when moved by said lug, and clutch-shifting mechanism for changing the connections of the cam-cylinder from rotation to reciprocation and vice versa, a projection from said clutch-shifting mechanism, said pawl being in line of movement of said clutch-shifting-mechanism projection and released when struck thereby.

46. In a circular-knitting machine of the character described, in combination, a needle-cylinder, fashioning-needles in said cylinder, mechanism to throw said fashioning-needles out of and into action for the purpose of narrowing and widening the fabric, non-fashioning needles in said cylinder, a cam-cylinder and means to rotate and reciprocate said cam-cylinder, of mechanism for actuating certain of

the fashioning-needles to form tuck-stitches, mechanism for actuating certain of the non-fashioning needles to form tuck-stitches, means to connect said mechanisms together so 5 that they will operate uniformly and simultaneously, and means adapted, during the operation of the machine, to throw the fashioning tuck-stitch mechanism out of operation without affecting the non-fashioning-needle 10 tuck-stitch mechanism.

47. In a circular-knitting machine of the character described, in combination, a needle-cylinder, fashioning-needles in said cylinder, mechanism to throw said fashioning-needles 15 out of and into action for the purpose of narrowing and widening the fabric, non-fashioning needles in said cylinder, a cam-cylinder and means to reciprocate and rotate said cam-cylinder, mechanism for actuating certain of 20 the non-fashioning needles to form tuck-stitches thereon, mechanism for actuating certain of the fashioning-needles to form tuck-stitches thereon, means to connect the two mechanisms together to operate uniformly, 25 and simultaneously.

48. In a circular-knitting machine of the character described, in combination, a needle-cylinder, fashioning-needles in said cylinder, mechanism to throw said fashioning-needles 30 out of and into action for the purpose of narrowing and widening the fabric, non-fashioning needles in said cylinder, a cam-cylinder and means to reciprocate and rotate said cam-cylinder, mechanism for actuating certain of 35 the non-fashioning needles to form tuck-stitches thereon, mechanism for actuating certain of the fashioning-needles to form tuck-stitches thereon, means to connect the two mechanisms together to operate uniformly and 40 simultaneously, and means to sever said connection.

49. In a circular-knitting machine of the character described, in combination, a needle-cylinder, fashioning-needles in said cylinder, mechanism to throw said fashioning-needles 45 out of and into action for the purpose of narrowing and widening the fabric, non-fashioning needles in said cylinder, a cam-cylinder and means to reciprocate and rotate said cam-cylinder, mechanism for actuating certain of 50 the non-fashioning needles to form tuck-stitches thereon, mechanism for actuating certain of the fashioning-needles to form tuck-stitches thereon, means automatically to connect the two mechanisms together to operate uniformly and 55 simultaneously.

50. In a circular-knitting machine of the character described, in combination, a needle-cylinder, fashioning-needles in said cylinder, mechanism to throw said fashioning-needles 60 out of and into action for the purpose of narrowing and widening the fabric, non-fashioning needles in said cylinder, a cam-cylinder and means to reciprocate and rotate said cam-cylinder, mechanism for actuating certain 65

of the non-fashioning needles to form tuck-stitches thereon, mechanism for actuating certain of the fashioning-needles to form tuck-stitches thereon, means to connect the two mechanisms together to operate uniformly 70 and simultaneously, and means automatically to sever said connection.

51. In a circular-knitting machine of the character described, in combination, a needle-cylinder, fashioning-needles in said cylinder, mechanism to throw said fashioning-needles 75 out of and into action for the purpose of narrowing and widening the fabric, non-fashioning needles in said cylinder, a cam-cylinder and means to reciprocate and rotate said cam-cylinder, mechanism for actuating certain of the non-fashioning needles to form tuck-stitches thereon, mechanism for actuating certain of the fashioning-needles to form tuck-stitches thereon, means automatically to connect the two mechanisms together to operate uniformly 80 and simultaneously, and means automatically to sever said connection.

52. In a circular-knitting machine of the character described, in combination, a needle-cylinder, fashioning-needles in said cylinder, mechanism to throw said fashioning-needles 85 out of and into action for the purpose of narrowing and widening the fabric, non-fashioning needles in said cylinder, a cam-cylinder and means to reciprocate and rotate said cam-cylinder, mechanism for actuating certain of the non-fashioning needles to form tuck-stitches thereon, mechanism for actuating certain of the fashioning-needles to form tuck-stitches thereon, means to connect the two mechanisms together to operate uniformly and 90 simultaneously, and means automatically to sever said connection and hold the fashioning tuck-stitch mechanism in a fixed position.

53. In a circular-knitting machine of the character described, in combination, a needle-cylinder, fashioning-needles in said cylinder, mechanism to throw said fashioning-needles 95 out of and into action for the purpose of narrowing and widening the fabric, non-fashioning needles in said cylinder, a cam-cylinder and means to reciprocate and rotate said cam-cylinder, mechanism for actuating certain of the non-fashioning needles to form tuck-stitches thereon, mechanism for actuating certain of the fashioning-needles to form tuck-stitches thereon, means to connect the two mechanisms together to operate uniformly and 100 simultaneously, and means automatically to sever said connection and hold the fashioning tuck-stitch mechanism in a fixed position.

54. In a circular-knitting machine of the character described, in combination, a needle-cylinder, fashioning-needles in said cylinder, mechanism to throw said fashioning-needles 105 out of and into action for the purpose of narrowing and widening the fabric, non-fashioning needles in said cylinder, a cam-cylinder and means to reciprocate and rotate said cyl- 110

inder, mechanism for actuating certain of the non-fashioning needles to form tuck-stitches thereon, mechanism for actuating certain of the fashioning-needles to form tuck-stitches thereon, means automatically to connect the two mechanisms together to operate uniformly and simultaneously, and means automatically to sever said connection and hold the fashioning tuck - stitch mechanism in a fixed position.

55. In a machine of the character described, in combination with the cam - cylinder and knitting-cam mechanism, the needle - lifting cam of which is pivotally attached to said cylinder, of a block secured to the cam-cylinder so as to be vertically movable, said block having a horizontal slot, said needle-lifting cam having a pin resting in said slot, said block having a cam - face projecting beyond said cam-cylinder, a lever adapted when brought against said cam-face to elevate said block, a second lever to which the first-mentioned lever is attached, the first-mentioned lever when struck being moved against the block projection and means to cause the first-mentioned

lever to be withdrawn from said block projection, when the second-mentioned lever is struck.

56. In a circular-knitting machine, in combination, a cam-cylinder, means to rotate and reciprocate said cam-cylinder, knitting-cam mechanism, a pivoted cam, forming part of the knitting-cam mechanism, adapted to yield in one direction of movement of the cam-cylinder, said pivoted cam being supported so as 35 to be vertically adjustable.

57. In a circular-knitting machine, in combination, a cam-cylinder, means to rotate and reciprocate said cam-cylinder, knitting-cam mechanism carried by said cylinder, the leading switch-cam of said knitting-cam mechanism being vertically adjustable.

In testimony of which invention I have hereunto set my hand at Philadelphia on this 23d day of October, 1902.

HARRY A. HOUSEMAN.
